CLAIM

The ornamental design for an electric sausage filler, as shown and described.

DESCRIPTION

FIG. 1 is a front, right, top perspective view of an electric sausage filler showing our new design;

FIG. 2 is a back, right, bottom perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof; and,

FIG. 8 is an enlarged bottom view thereof.

The broken lines shown on the drawings depict portions of the electric sausage filler that form no part of the claimed design.

1 Claim, 8 Drawing Sheets
